(57) **CLAIM**

The ornamental design for portion of an adjustable headset for an electronic device, as shown and described.

DESCRIPTION

FIG. 1 is a front perspective view of a portion of an adjustable headset for an electronic device showing my new design, in an open position;

FIG. 2 is a front view thereof;

FIG. 3 is a side view thereof;

FIG. 4 is a top plan view thereof;

FIG. 5 is a bottom plan view thereof; and,

FIG. 6 is a front perspective view thereof in an alternate folded closed position.

The broken line portions shown in FIGS. 1 through 7 illustrate environmental subject matter only and form no part of the claimed design.

1 Claim, 5 Drawing Sheets
